HARRY E. DUNKELBERGER AND NICK WITTIER, OF WEIRTON, WEST VIRGINIA.

FURNACE-SLAGGING APPARATUS.

Application filed July 15, 1927. Serial No. 206,031.

This invention relates broadly to furnace slagging apparatus, and more specifically to a furnace embodying apparatus whereby linings of refractory material may be introduced for protecting the walls thereof.

The primary object of the invention is to provide, in association with the front or rear walls of an open hearth furnace, mechanical means whereby a lining of refractory material, as dolomite, may be introduced within the furnace for protecting said walls from the intense heat of the furnace.

A further object is to provide a furnace which embodies therein means by which slagging of the walls thereof may be accomplished with facility and without interfering with the normal operation thereof.

In describing the invention in detail, reference is herein had to the accompanying drawings, in which—

Figure 1 is a vertical section of a furnace equipped with our invention; and—

Figures 2 and 3 are sections taken, respectively, on lines 2—2 and 3—3, Fig. 1.

Referring to said drawings, 1 designates the side wall and 2 the arch of a furnace of open hearth type, said wall being abutted exteriorly by upright buckstays 3, as ordinarily.

Suitably mounted upon the buckstays 3 at an appropriate elevation is a horizontally disposed metal slab 4 of materially less thickness than the wall 1, and rigidly carried in parallel relation to said slab at a spaced distance from the inner face of the latter is a horizontal channel iron skewback 6 which constitutes the support for the adjacent edge portion of the furnace arch or roof 2. Blocks 5 located at suitably spaced intervals between said slab 4 and said skewback 6 serve to space said members apart to provide therebetween a passage, or a series of aligned passages, 7 through which the dolomite slagging, or other suitable material may be introduced within the furnace, as will hereinafter be described. Said blocks 5 are secured in place by means of bolts 8 which also serve to maintain the skewback in fixed relation to the wall-slab 4, as shown. Said skewback is additionally supported by substantially upright tie-rods 9 attached to a suitable overlying part of the furnace structure, as by cross-beams 10 connecting the upper ends of oppositely disposed buckstays 3.

Extending longitudinally of the furnace

above the level of the arch 2 is a bin or hopper 11 which communicates along its bottom end with the passage 7, the same being designed for the reception of the dolomite or other material 12 which is to be employed as an internal slagging for the underlying furnace wall 1. A damper-like valve or gate comprising a plate or series of aligned plates 13, slidably upon a side wall of the hopper to and from closing relation to the bottom opening of the latter, is designed to control the feed of the slagging material to said passage 7. Rods 14 connected to said plate or plates 13 provide means whereby the latter may be positioned by hand as desired.

The arch-supporting skewback 6 is spaced from the top of the adjacent wall 1, forming therebetween a longitudinally extending space 15 in which is mounted in aligned relation a series of closures or valves 16 whereby the lower ends of the passages 7 may be opened and closed. Each of said valves 16, as herein shown, is constructed of heavy sheet metal and is made of hollow container form so that it is adapted to be cooled by flowing water, such water being admitted thereto adjacent to one end by means of a thereby-carried inlet pipe 17 and being discharged therefrom at a point adjacent to its opposite end by means of a thereby-carried outlet pipe 18. Said pipes 17 and 18 have flexible connection, as through lengths of rubber tubing 17' and 18', respectively, with suitably located water supply and outlet pipes (not shown).

The valves 16 are disposed in substantially abutting relation, each thereof extending from the center line of the inner face of one buckstay 3 to the center line of the next adjacent buckstay, as shown in Fig. 3. Each of said valves has a substantially flat top portion 16^a and 16^b, the latter being seated adjacent to its opposite ends upon supports 19 constituted by pipes 19 of U shape which are directed inwardly through the buckstays and which, except at the curved connecting portion 19^a thereof, have their uppermost surfaces substantially flush with the level of the top of the wall 1. Said portion 19^a is elevated slightly with respect to said level, as shown, the adjacent parallel portions of the pipe being curved on a radius corresponding to that of the adjacent convex bottom portion of the overlying valve 16.

In the normal position thereof, each of the

valves 16 occupies the position shown in broken lines in Fig. 1 wherein it wholly closes both the space 15 and the overlying passage 7 against the outward passage from the furnace interior of heat and other products of combustion, the innermost portion of the valve, which, in cross section, has the form of a tapered nose 16^a, seating in underlying relation to the arch 2, or to the skewback 6. When the valve is rotated to the full line position shown in Fig. 1, effected by hand power applied through the pipes 17 and 18 employed as levers, the rear edge of the flat top portion 16^a of the valve 15 seats against the lower edge of the slab 4, so that said valve closes the space 15 against the outward passage therethrough of products of combustion, and the passage 7 is opened to permit substantially unobstructed downward flow from said passage of slagging material admitted from the hopper 11 past the gate 13. In said position of the valve the flat top portion 16^a is downwardly and inwardly inclined and constitutes, in effect, a short chute over which the slagging material passes by gravity to the interior of the furnace and by which said material is deposited in close proximity to the wall 1 where it piles up, or becomes banked, for performing its function as a protective lining for said wall.

In practice, the slagging material is deposited in the hopper 11 while the gate 13 occupies closed position. When slagging of the furnace wall 1 is desired, the valve or valves 16 are first rotated to open position, following which the gate or gates are opened. When the required amount of slagging material has been admitted, or when, for any reason, it is desired to stop the flow of said material, the gates are first closed and then when the passage or passages 7 have been cleared of the material, the valve or valves 16 are rotated to their closed positions.

The pipes 19 are carried by the various buckstays, as shown, and constitute conductors for running water by which they are cooled.

It will be noted that the operation of slagging the furnace may be performed by the use of the structure described without in any way interrupting or retarding the continued operation of the furnace and with no appreciable loss of heat. Moreover, its use effects the elimination of the exhausting manual labor heretofore employed for depositing the slagging material and prevents the considerable cooling of the furnace which results from the opening of the furnace doors necessitated in such manual slagging.

What is claimed is—

1. In a furnace of the character described, a wall having therein beneath the arch there-

of a longitudinally extending opening, a hopper for slagging material located over said arch, gravity feed passages leading past said arch from said hopper to said opening, and a rotary valve in said opening adapted, 70 in one position, to close said passages against downward feed of said material and, in another position, to open said passages and to direct material gravitating through the latter to a position for banking against the 75 inner face of said wall.

2. In a furnace of the character described, a wall having therein beneath the arch thereof a longitudinally extending opening, a hopper for slagging material, located over 80 said arch, gravity feed passages leading past said arch from said hopper to said opening, and a rotary valve in said opening adapted, in one position, to close the lower ends of 85 said passages and, in another position, to permit gravity flow of said material into lining-forming relation to the inner face of said wall.

3. In a furnace of the character described, a wall having therein beneath the arch thereof a longitudinally extending opening, a hopper for slagging material located over 90 said arch, gravity feed passages leading past said arch from said hopper to said opening, and a rotary valve in said opening adapted, 95 in one position, to close the lower ends of said passages and, in another position, to permit gravity flow of said material into lining forming relation to the inner face of said wall, said valve having a hollow water- 100 cooled construction.

4. In a furnace of the character described, a slag-container located over the furnace arch, gravity feed passages leading from said container to the interior of the furnace 105 adjacent to the top of a wall of the latter, and a horizontally disposed rotary valve whereby said passages may be opened and closed.

5. In a furnace of the character described, 110 a slag-container located over the furnace arch, gravity feed passages leading from said container to the interior of the furnace adjacent to the top of a wall of the latter, and a horizontally disposed rotary valve 115 whereby said passages may be opened and closed, a surface of said valve forming a reflecting chute for gravitating slag.

6. In a furnace of the character described, 120 a slag-container located over the furnace arch, gravity feed passages leading from said container to the interior of the furnace adjacent to the top of a wall of the latter, and a horizontally disposed rotary valve of hollow water-cooled form arranged to control the admission of slag through said passages.

7. In a furnace of the character described, 125 an arch, means whereby said arch is supported relative to an adjacent furnace wall 130

for forming intermediate vertical passages, a hopper communicating through its bottom with said passages, said wall having therein a longitudinally extending opening through 5 which communication may be had between said passages and the interior of the furnace, and a valve mounted for rotary movement in said opening for controlling such communication.

10. 8. In a furnace of the character described, an arch, means whereby said arch is supported relative to an adjacent furnace wall for forming intermediate vertical passages, a hopper for feeding material to said passages, a shiftable gate for controlling communication between said hopper and said passages, said wall having below the arch an opening extending horizontally from end to end thereof, and a valve disposed in and 15 closing said opening against the escape from the furnace of products of combustion, said valve being shiftable into and out of closing 20 relation to said passages.

9. In a furnace of the character described, 25 an arch, means whereby said arch is supported relative to an adjacent furnace wall for forming intermediate vertical passages, a hopper for feeding material to said passages, a shiftable gate for controlling communication between said hopper and said 30 passages, said wall having below the arch an

opening extending horizontal from end to end thereof, and a valve disposed in and closing said opening against the escape from the furnace of products of combustion, said 35 valve being shiftable into and out of closing relation to said passages, and, when occupying passage-opening position, being adapted to direct such material to a position wherein it becomes banked to form a protective internal lining for said wall. 40

10. In a furnace of the character described, an arch, means whereby said arch is supported relative to an adjacent furnace wall for forming intermediate vertical passages, a hopper for feeding material to said passages, a shiftable gate for controlling communication between said hopper and said passages, said wall having below the arch an opening extending horizontally 45 from end to end thereof, and a valve disposed in and closing said opening against the escape from the furnace of products of combustion, said valve being bodily rotatable relative to said passages for controlling 50 the flow of material from the latter and being artificially cooled. 55

In testimony whereof we affix our signatures.

HARRY E. DUNKELBERGER.
